SEAM REEFING TOOL

Leonard F. Woodel, Hollis, N. Y.

Application April 5, 1956, Serial No. 576,459

2 Claims. (Cl. 30—293)

The present invention relates in general to seam reefing tools, and more particularly to hand tools for raking calked joints in decking and sides of boats and the like preparatory to recalking joints.

The practice of calking joints or seams between adjacent strips of deck planking or side planking in boats involves the wedging of a yarn of oakum or cotton twist or wicking between the adjacent edges of the planking and then paying the same with a calking compound such as melted pitch or other fluid composition which subsequently sets to form a yieldable filler between the joints. The wedging of the oakum yarn or cotton wicking into the seam is an extremely tedious and time-consuming job. Adequate maintenance of boat hulls and decking many times can be effected by merely cleaning the calking compound from the seams while leaving the oakum yarn or cotton wicking wedged into the seam and applying a new calking compound filler into the clean joint, thereby drastically reducing the time and labor involved in boat maintenance as the more time-consuming process of wedging new yarn or wicking into the seam is not performed.

An object of the present invention is the provision of a tool for raking calked seams to remove plastic calking compound therefrom without disturbing the calking yarn or wicking lodged in the seam.

Another object of the present invention is the provision of a novel seam reefing tool for removing plastic calking compound from calked seams without disturbing calking yarn or wicking therein, wherein means are provided for precisely regulating the depth of insertion of the tool into the calked seam to penetrate only to the depth of the calking compound.

Another object of the present invention is the provision of a seam reefing tool for raking calked seams free of plastic calking compound without disturbing the calking yarn or wicking therein, wherein means are provided to adapt the tool to rake only plastic compound from seams wherein the edges of bevelled edge planking are spaced different distances from each other.

Other objects, advantages and capabilities of the present invention will become apparent from the following detailed description taken in conjunction with the accompanying drawing illustrating one preferred embodiment of the invention.

In the drawing:

Figure 1 is a perspective view of a seam reefing tool embodying the present invention, viewed from one side thereof;

Figure 2 is a perspective view of the seam reefing tool, viewed from the other side thereof;

Figure 3 is an end elevation view of the seam reefing tool, illustrated in working association with a calked seam; and

Figure 4 is a longitudinal transverse section view taken along the line 4—4 of Figure 3.

Referring to the drawing, wherein like reference characters designate the corresponding parts throughout the several figures, the seam reefing tool of the present invention

2

tion, generally designated by the reference character 10, comprises an elongated handle 11 from one end of which projects a tool head, generally indicated at 12. The tool head 12 is generally in the shape of a deformed Y, having 5 a neck portion 13 from which projects an integral spike 14 which tapers to a point at the lower end of the spike and is provided with screw threads along the opposite tapered surfaces thereof adapted to be received in the threaded bore 15 of a sleeve 16 embedded in the handle 10. 11. A reinforcing sleeve 17 extends around the upper portion of the handle in which the threaded sleeve 16 is embedded.

Projecting along curved paths from the opposite end of the neck 13 of the tool head 12 are a pair of arms 18, 19 which terminate in sharp seam raking points 20 and 21, respectively. As will be apparent from Figures 1 and 2 of the drawing, the edges 22 of the raking points 20 and 21 which are adjacent the handle 11 form an acute angle with the axis of the tool so as to cam calking 20 compound dislodged from the seam upwardly out of the seam when the tool 10 is positioned for use approximately as illustrated in Figures 1 and 2. The sides of the arm 18 adjacent the raking point 20 are bevelled, as indicated at 23, along planes converging toward the apex of the point 20 to provide a point having a thickness of $\frac{1}{16}$ inch at its apex, and the sides of the arm 19 adjacent the raking point 21 are tapered, as indicated at 24, to provide an apex having a thickness of $\frac{1}{8}$ inch. The inclination of the bevelled surfaces 23 and 24 is designed to correspond substantially with the conventional slight bevel of the edges of boat deck and side planking of the type designed to produce a V-shaped calking seam.

In order to limit the depth of projection of the apex of either of the raking points 20, 21 into a calking seam, 35 such as that indicated at 25 in Figure 3, an adjustable stop arm 26 is secured at one end thereof to the neck 13 at a point intersecting the axis of the tool and adjacent the lower end of the neck 13 by means of a screw 27 having a threaded shank 28 which is threaded into a complementary threaded aperture in the neck 13 of the tool head 12.

In the use of the tool, the screw 27 is loosened so as to permit the stop arm 26 to rotate freely about the shank 28 of the screw 27, and either the raking point 20 or 21, whichever is appropriate for the dimensions of the calking seam 25, is forced into the seam and raked a short distance along the length thereof to remove plastic calking compound from the seam 25 and expose the surface of the calking yarn or wicking, indicated generally at 29. 50 With the raking point 20 or 21 then seated in the calking seam 25 to an appropriate depth to just contact the surface of the calking yarn or wicking 29, the stop arm 26 is then rotated to engage the surface of the deck planking or side planking, indicated generally at 30, and the screw 55 27 is then tightened to frictionally clamp the stop arm 26 in this position of adjustment. The stop arm 26 then serves as an abutment guide which limits the depth of penetration of the raking point 20 or 21 into the seam 25 so that as the raking point is drawn rapidly along the length of the seam, only the plastic calking compound is dislodged from the seam, and the calking yarn or wicking 29 remains undisturbed as the raking point cannot penetrate a sufficient distance into the seam to dislodge the yarn or wicking.

The smoothly curved upper edges of the arms 18, 19 rising from the depression at the juncture of the arms also affords convenient surfaces for rolling the calking cotton down tight into the seams where heavier planking is encountered and calking cotton is to be seated in the seams before the calking compound is applied.

While only one preferred embodiment of the invention has been particularly shown and described, it is apparent

that other modifications may be made in the invention without departing from the spirit and scope thereof, and it is desired, therefore, that only such limitations shall be placed thereon as are imposed by the prior art and are set forth in the appended claims.

I claim:

1. A reefing tool for raking calking compound from calked seams between deck and hull planking of boats and the like and leaving undisturbed calking yarn in the seams, comprising an elongated handle, a tool head formed of a metal plate in the shape of a modified Y having a neck portion removably affixed to said handle and oppositely projecting arms extending along curved paths and terminating in sharp raking points, the edges of the terminal portions of said arms adjacent said handle forming acute angles with the axis of said handle, and the portions of said arms adjacent said raking points having bevelled sides converging toward said raking points to produce points of dissimilar thickness, said bevelled sides and raking points defining outwardly converging arm portions of truncated V-shaped cross-section complementary to portions of V-shaped grooves formed between adjacent edges of bevel edge boat decking and planking and adjustable depth gauge means affixed to said neck portion positionable to selectively extend alongside the terminal portions of either one of said arms in spaced relation to said raking points and terminating in an edge forming a stop surface for engaging the surfaces of planking adjacent calked seams and limit the depth of penetration of said raking points into the seams.

2. A reefing tool for raking calking compound from calked seams between deck and hull planking of boats and the like and leaving undisturbed calking yarn in the seams, comprising an elongated handle, a tool head formed of a metal plate in the shape of a modified Y

having a neck portion removably affixed to said handle and oppositely projecting arms extending along curved paths and terminating in sharp raking points, the edges of the terminal portions of said arms adjacent said handle

5 forming acute angles with the axis of said handle, and the portions of said arms adjacent said raking points having bevelled sides converging toward said raking points to produce points of dissimilar thickness, said bevelled sides and raking points defining outwardly converging 10 arm portions of truncated V-shaped cross-section complementary to portions of V-shaped grooves formed between adjacent edges of bevel edge boat decking and planking and an adjustable stop lever journaled adjacent one end thereof on a screw threadedly coupled to said 15 neck portion at a point intersecting the axis of said handle, said screw serving as adjustable clamping means to frictionally lock said stop lever in selected positions wherein the free end of said stop lever extends alongside the terminal portion of one of said arms spaced rearwardly of the raking point thereon to form a bearing stop 20 for engaging the surfaces of planking adjacent calked seams and limit the depth of penetration of the adjacent raking point into the seam.
